AUTOMATIC YARN WINDING MACHINE

John Robert Grady, Cheadle Hulme, and Harold L. Muschamp, Bramhall, England; said Grady assignor to said Muschamp

Application June 16, 1949, Serial No. 99,482

Claims priority, application Great Britain June 17, 1948

20 Claims. (Cl. 242—41)

1. This invention relates to automatic winding machines such as are known as quill winders, pin winders, spool winders, core winders or weft winders of the kind in which a full quill, pin or other package after winding is removed from the winding station and an empty tube, bobbin or other core automatically inserted in its place, whereupon winding is again automatically started, the cycle of operations being controlled by an "automaton". The invention, while primarily applicable to, and hereinafter described as applied to, yarn winding machines, is applicable to winding machines for any other filament such as a wire.

Hitherto, it has been the practice in all such machines to release the full package, as by withdrawing the tip end or tail stock at the winding station, so that the package can fall out of the winding station.

This arrangement, while reasonably practical for pins or relatively heavy packages, has the disadvantage that it is not positive. Even with pins it has been known for them not to fall completely clear and thereby obstruct the reloading of the winding station. With light packages, such as small quills, this uncertainty would be even more troublesome as the tension in the yarn or possibly even the fit of the core in the machine, or both together, may be sufficient to hold the bobbin completely or at least partly in the winding station. Other points of importance which are or can be affected by such uncertainty are: the trapping of the yarn for restarting winding, maintaining of yarn tension so as to prevent undesired action of "knock off" mechanism; and, possibly the unwinding of what might be a substantial length of the yarn leaving an unnecessary long free end.

The object of the present invention is to overcome the aforesaid disadvantages.

According to the invention an automatic winding machine of the kind referred to is characterised by means for gripping the full package while in the winding station after winding has stopped and positively removing the same from the winding position.

The machine aforesaid may be further characterised in that the gripping means is arranged to hold the full package adjacent to the winding station after removing it therefrom, but so as not to obstruct reloading of the machine and so maintain a predetermined tension and direction of the yarn during reloading; or further characterised in that the gripping means is fitted with rollers whereby they can easily be engaged by a rolling motion with the package yet provide fric-

tional grip against endwise movement of the package; or further characterised in that the gripping means is arranged so as to move further away from the winding station after the reloading operation and so as thereby to cause release of its package; or further characterised in that the gripping means embodies an ejector for the package adapted to contact a stationary part with the said further movement of the gripping means.

In the accompanying drawings:

Fig. 1 is a plan;

Fig. 2 is a part sectional side elevation; and

Fig. 3 is an end view showing one example of a winding machine made in accordance with the invention;

Fig. 4 is a detail end elevation of part of the same winding machine;

Fig. 5 is a detail section of the winding head spindle.

In the example of the invention shown in the drawings, fixed to the winding head below and off-set from the winding spindle 10 is a rod 11 parallel with the axis of the spindle. The spindle is provided with a head 10' having a flange 10". Slidably and rotatably mounted on such rod is a sleeve 12 at one end of which is an arm 13 having a head 13' on which are a pair of clamps 14 each holding a U-shaped spring wire 15, the ends of each of which are turned in to hold a gripping roller 16. The clamps can be released for adjusting the position and tension of the gripping rollers. The clamps consist of plates secured by screws 14', which clamps hold the wire in a groove in the head so that the wires may be removed for the purpose of changing them for others of different size. The arm 13 is also adjustably secured on the end of the sleeve 12 so that the position of the rollers 16 relative to the package 17 may be adjusted both radially and axially of the sleeve. At the other end of the sleeve is a toothed pinion 18 having a flange 18' at each side of larger diameter than the teeth.

Immediately below the rod 11 is a further rod 19 which is both slidable and rotatable and is carried at one end by a bracket 20 attached to the winding head. The tail or tip end bracket 21 of the winding machine is carried by the rod 11 and a further stiff rod 22 located above the rod 11. The tail stock 23 which carries the tip end 23' is slidably mounted on these two rods 11 and 22 and is adapted to be moved positively backwards or forwards to advance or retract the tail stock or tip end relative to the quill, such movement being effected from the automaton by a push rod.

24, of flat cross section, connected to the tail stock 23. Secured to the shaft 19 is a toothed quadrant 25 the toothed edge of which is located between the flanges 18' and is in mesh with the pinion 18. On the end of the shaft 19 adjacent to the headstock is fixed an arm 26 carrying a bowl 27 (see Fig. 2) which is engaged between cam edges 28, one only of which is shewn and which cam is driven by the automaton, such cam providing oscillatory movement in both directions of the shaft 19 and through the quadrant 25 and pinion 18 amplifies oscillatory movement of the sleeve 12. Near the other end of the shaft 19 are fixed a pair of collars 29 spaced slightly apart and adapted to be engaged by a peg 30 on a lever 31 which is pivoted by one end to a bracket 32 attached to the end bracket 21. The other end of the lever is forked and is engaged with a stud 33 (see Figs. 1 and 2) on the lower part of the tailstock 23.

Referring to Fig. 3, it will be seen that the arm 13 has an ejector 34 of T-shape (see also Fig. 1), the tail of which is forked, the ends of the fork being bent round to clip over a pivot pin 35 about which the ejector is free to pivot. In the head 13' of the arm is an adjustable screw stop 36 the end of which forms a stop to position the ejector so that the head of the ejector 34 and the two rollers 16 provide triangulated holding points for the quill 17. On the rod 19 are fixed a pair of blocks 37, which are in register with the arm 13, so that, as described later, such arm can move between them and the ejector can be engaged with the ends of the blocks for ejection of the quill.

On the shaft 22 is slidably mounted a slide 38 to which is attached a collector fork 39 the slide having a key 40 sliding in a key-way 41 in the shaft. The slide 38 is adapted to be moved along the rod by a link 42 connected to the automaton.

In operation, assume a quill is in the winding station and winding has just been stopped by any suitable measuring mechanism which at the same time starts the automaton, such mechanism being well known in automatic winders. The cam faces 28 commence to rotate and turn the shaft 19 which through the quadrant 25 and pinion 18 causes the arm 13 to rise pushing the rollers 16 over the quill 17 and so that the head of the ejector 34 rests against the underside of the quill, giving a triangulated contact with the quill while the latter is still between the centres of the winding head. While the arm 13 is held in this position, the tailstock 23 is pushed back by the automaton through the push rod 24 which movement also, through the lever 31, peg 30 and collars 29 pulls back the rod 19 through about half the distance of the movement of the tailstock 23. The rod 19 through the quadrant 25 and flanges 18' moves the sleeve 12 with its arm 13 along the rod 11 through such half distance. Thus the tip end 23' is withdrawn from the quill 17 and the quill is withdrawn from the spindle head 10' the quill being still held substantially in axial alignment with the centres of the winding head. The cam faces 28 now operate to turn the arm 13 lowering the quill into a waiting position in which the ejector 34 is about to engage the blocks 37 for ejection and while the quill is held in this waiting position the automaton draws the collector fork 39 over the top of the quill so that its hooked forked ends engage the thread and draw it towards the winding spindle, such thread (not shewn) being still in tension between the quill and a yarn guide not shewn. The thread therefore assumes a substantially vertical and predetermined position

between the hooks and is brought by them towards the spindle head 10' until it engages the flange 10² for the purpose of enabling the thread to be brought into position for gripping between the head 10' and the flange 10² as described in detail in co-pending application Serial No. 99,481.

After a new tube or core has been brought into position between the tip end 23' and the winding spindle head 10', (means not shewn) the automaton now pulls the rod 24 closing the tip end 23' onto the new core and this movement of the tailstock also causes return sliding movement of the gripper arm 13 but without performing any function. Thread cutting mechanism is then brought into action and the automaton also returns the collector fork to its original position and the means not shewn which brought the new core to the winding station.

Finally, the cam faces 28 turn the sleeve 12 lowering the arm 13 for the ejection of the full quill which is caused by the engagement of the ejector 34 with the blocks 37 arresting its movement while the arm 13 is lowered further to its normal, or idle position. The ejected quill falls into a basket or other suitable receptacle.

As shewn in Fig. 5 the winding spindle 10 the end of which is shewn in chain line is drilled to receive alternative sizes and shapes of adaptor heads 10' according to the tube to be used. The present device is therefore shewn as an adaptor head and consists of a spindle portion 43 with a screw-threaded extension 44 and spigot tail 45 adapted for fixing in location in the end of the spindle. The spindle portion 43 has a flange 10² and is formed with a cylindrical axial end socket 46. Slidably located in such end socket is a plunger 10' having a tail 47 located in the socket, a cross pin 48 limiting its axial movement and constraining it to rotate with the spindle end 43. In the socket is a light compression spring 49. The plunger 10' has a conical portion 50 the base of which is formed with a peripheral rim 50' adapted to lie against the end face of the flange 10², so that such adjacent faces form a yarn-receiving and clamping means. At the outer end, the plunger 10' is formed with a small extension or centre 51 of a size suitable to fit into and locate the end of the quill tube 52, behind which extension is a groove for a friction ring 53.

The tailstock is of known construction and includes a free running spindle 54 carried in a bush 55 slidably mounted in a housing 56 with limited cushion spring axial movement, (the spring not being shewn), the housing 56 being adjustable in the tailstock 23 which latter is adapted to be mechanically advanced and withdrawn by the automaton as already described and the cushion spring being partially compressed when a quill tube is in position. The spindle has an adaptor head or tip end 23' which is changeable for different sizes and shapes of tube.

In operation, as soon as the tailstock is withdrawn by the automaton, the full quill is released and the plunger 10' is urged forward by its spring 49 to open the base of the cone 50 from the flange 10². The parts are in this position ready to receive the yarn between them when it is brought against the flange by the hooked collector arm 39.

What we claim is:

1. A winding station for an automatic winding machine for producing a wound package by winding a filament on to a core while held between centres, comprising package-gripping means, pivotal mounting means therefor having an axis parallel to and adjacent to the said centres, means for moving the package gripping

means into gripping engagement with a wound package held between said centres, said centres comprising a winding spindle and tail stock respectively, means for effecting relative movement of said winding spindle and said tail stock towards and away from one another to hold and release the cores respectively, and means for moving the package-gripping means away from the centres after engagement by said package-gripping means to carry the wound package to a waiting position parallel to the winding position and so that the filament leading thereto is held in tension in a predetermined position for further manipulation.

2. A winding station for an automatic winding machine for producing a wound package by winding a filament on to a core while held between centres, comprising package-gripping means, pivotal mounting means therefor having an axis parallel to and adjacent to the said centres, means for moving the package-gripping means into gripping engagement with a wound package held between said centres, said centres comprising a winding spindle and tail stock respectively, means for effecting relative movement of said winding spindle and said tail stock towards and away from one another to hold and release the cores respectively, means for moving the package-gripping means away from the centres after engagement by said package-gripping means to carry the wound package to a waiting position parallel to said winding position and so that the filament leading thereto is held in tension in a predetermined position for further manipulation and means for subsequently ejecting the wound package from the package-gripping means.

3. A winding station for an automatic winding machine for producing a wound package by winding a filament on to a core while held between centres, comprising package-gripping means, pivotal mounting means therefor having an axis parallel to and adjacent to the said centres, means for moving the package-gripping means into gripping engagement with a wound package held between said centres, said centres consisting of a winding spindle and tail stock respectively, means for moving the tail stock axially of, and away from, the core to withdraw it from the core, means for moving the package-gripping means towards the tail stock, for a distance less than the movement of the latter, so as to move the package axially in alignment with the centres and withdraw the core from the winding spindle and means for moving the package-gripping means away from the centres to carry the wound package to a waiting position parallel to said winding position and so that the filament leading thereto is held in tension in a predetermined position for further manipulation.

4. A winding station for an automatic winding machine for producing a wound package by winding a filament on to a core while held between centres, comprising package-gripping means adjacent to the said centres, means for moving the package-gripping means into gripping engagement with a wound package held between said centres, said centres consisting of a winding spindle and tail stock respectively, means for moving the tail stock axially of, and away from, the core to withdraw it from the core, means for moving the package-gripping means towards the tail stock, for a distance less than the movement of the latter, so as to move the package axially in alignment with the centres and withdraw the core from the winding spindle means for mov-

ing the package-gripping means away from the centres to carry the wound package to a waiting position so that the filament leading thereto is held in tension in a predetermined position for further manipulation, filament collector means normally adjacent the tailstock and means for moving the filament collector means towards the winding spindle so as to engage the filament and carry it to a position adjacent such spindle.

5. A winding station for an automatic winding machine for producing a wound package by winding a filament on to a core while held between centres, comprising package-gripping means adjacent to the said centres, means for moving the package-gripping means into gripping engagement with a wound package held between said centres consisting of a winding spindle and tail stock respectively, means for moving the tailstock axially of, and away from, the core to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound package to a waiting position so that the filament leading thereto is held in tension in a predetermined position for further manipulation, filament-receiving and clamping means on the winding spindle, filament collector means normally adjacent the tailstock and means for moving the filament collector means towards the winding spindle so as to engage the filament and carry it to a position adjacent such spindle, and so that such filament enters the said filament-receiving and clamping means on the spindle.

6. A winding station for an automatic winding machine for producing a wound package by winding a filament on to a core while held between centres, comprising package-gripping means adjacent to the said centres, means for moving the package-gripping means into gripping engagement with a wound package held between said centres, said centres consisting of a winding spindle and tail stock respectively, means for moving the tailstock axially of, and away from, the core to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound packages to a waiting position so that the filament leading thereto is held in tension in a predetermined position for further manipulation, filament-receiving and clamping means on the winding spindle, comprising a flange secured to the winding spindle and a plunger head axially movable thereto but constrained to rotate with the spindle, filament collector means normally adjacent the tailstock, means for moving the filament collector means towards the winding spindle so as to engage the filament and carry it to a position adjacent such spindle, and so that such filament enters between the said flange and plunger head.

7. A winding station for an automatic winding machine for producing a wound package by winding a filament on to a core while held between centres, comprising package-gripping means adjacent to the said centres, means for moving the package-gripping means into gripping engage-

ment with a wound package held between said centres, said centres consisting of a winding spindle and tailstock respectively, means for moving the tailstock axially of and away from the core to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound package to a waiting position so that the filament leading thereto is held in tension in a predetermined position for further manipulation, filament-receiving and clamping means on the winding spindle, comprising a flange secured to the winding spindle and a plunger head axially movable thereto but constrained to rotate with the spindle, a light spring normally holding the plunger head away from the flange but adapted to be over-powered by axial holding pressure on the core, filament collector means normally adjacent the tailstock and means for moving the filament collector means towards the winding spindle so as to engage the filament and carry it to a position adjacent such spindle and so that such filament enters between the said flange and plunger head.

8. A winding station for an automatic winding machine for producing a wound package by winding a filament on to a core while held between centres, comprising package-gripping means adjacent to the said centres, means for moving the package gripping means into gripping engagement with a wound package held between said centres, said centres consisting of a winding spindle and tailstock respectively, means for moving the tailstock axially of, and away from, the core to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound package to a waiting position so that the filament leading thereto is held in tension in a predetermined position for further manipulation, filament-receiving and clamping means on the winding spindle, comprising a flange secured to the winding spindle and a plunger head axially movable thereto but constrained to rotate with the spindle, a light spring normally holding the plunger head away from the flange but adapted to be over-powered by axial holding pressure on the core, filament collector means normally adjacent the tailstock, means for moving the filament collector means towards the winding spindle so as to engage the filament and carry it to a position adjacent such spindle and so that such filament enters between the said flange and plunger head, and means for moving the tailstock to grip a new core between the centres and cause the core to push back the plunger head on to the filament.

9. A winding station for an automatic winding machine for producing a wound package by winding a filament on to a core while held between centres, comprising package-gripping means adjacent to the said centres, means for moving the package-gripping means into gripping engagement with a wound package held between said centres, said centres consisting of a winding spindle and tailstock respectively, means for moving the tailstock axially of, and away from, the core

to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound package to a waiting position so that the filament leading thereto is held in tension in a predetermined position for further manipulation, filament-receiving and clamping means on the winding spindle, comprising a flange secured to the winding spindle and a plunger head axially movable thereto but constrained to rotate with the spindle, a light spring normally holding the plunger head away from the flange but adapted to be over-powered by axial holding pressure on the core, filament collector means normally adjacent the tailstock, means for moving the filament collector means towards the winding spindle so as to engage the filament and carry it to a position adjacent such spindle and so that such filament enters between the said flange and plunger head, means for moving the tailstock to grip a new core between the centres and cause the core to push back the plunger head on to the filament, and means for returning the filament-collector to the tailstock end of the machine before commencing winding.

10. A winding station for an automatic winding machine for producing a wound package by winding a filament on to a core while held between centres, comprising package-gripping means adjacent to the said centres, means for moving the package-gripping means into gripping engagement with a wound package held between said centres, said centres consisting of a winding spindle and tailstock respectively, means for moving the tailstock axially of, and away from, the core to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound package to a waiting position so that the filament leading thereto is held in tension in a predetermined position for further manipulation, filament-receiving and clamping means on the winding spindle, comprising a flange secured to the winding spindle and a plunger head axially movable thereto but constrained to rotate with the spindle, a light spring normally holding the plunger head away from the flange but adapted to be over-powered by axial holding pressure on the core, filament collector means normally adjacent the tailstock, means for moving the filament collector means towards the winding spindle so as to engage the filament and carry it to a position adjacent such spindle and so that such filament enters between the said flange and plunger head, means for moving the tailstock to grip a new core between the centres and cause the core to push back the plunger head on to the filament, and means for returning the filament-collector to the tailstock end of the machine before commencing winding and means for ejecting the wound package from the package-gripping means.

11. A winding station for an automatic winding machine for producing a wound package by winding a filament on to a core while held between centres, comprising package-gripping

means pivotal mounting means therefor having an axis parallel to and adjacent to the said centres, means for moving the package-gripping means into gripping engagement with a wound package held between said centres, means for releasing the core of the wound package from between centres after engagement by said package-gripping means, means for moving the package-gripping means away from the centres to carry the wound package to a waiting position parallel to the winding position and so that the filament leading thereto is held in tension in a predetermined position for further manipulation and means for ejecting the wound package from the package-gripping means, said package-gripping means comprising a pair of resiliently mounted rollers which, with the ejection means provide a triangulated hold for the package.

12. A winding station for an automatic winding machine for producing a wound package by winding a filament on to a core while held between centres, comprising package-gripping means, pivotal mounting means therefor having an axis parallel to and adjacent to the said centres, means for moving the package-gripping means into gripping engagement with a wound package held between said centres, said centres consisting of a winding spindle and tailstock respectively, means for moving the tailstock axially of, and away from, the core to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound package to a waiting position parallel to the winding position and so that the filament leading thereto is held in tension in a predetermined position for further manipulation and means for ejecting the wound package from the package-gripping means, said package-gripping means comprising a pair of resiliently mounted rollers which, with the ejection means, provide a triangulated hold for the package.

13. A winding station for an automatic winding machine for producing a wound package by winding a filament on to a core while held between centres, comprising package-gripping means adjacent to the said centres, means for moving the package gripping means into gripping engagement with a wound package held between said centres, said centres consisting of a winding spindle and tailstock respectively, means for moving the tailstock axially of, and away from, the core to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound package to a waiting position so that the filament leading thereto is held in tension in a predetermined position for further manipulation, filament-receiving and clamping means on the winding spindle, comprising a flange secured to the winding spindle and a plunger head axially movable thereto but constrained to rotate with the spindle, a light spring normally holding the plunger head away from the flange but adapted to be over-powered by axial holding pressure on the core, filament collector means normally adjacent the tailstock,

means for moving the filament collector means towards the winding spindle so as to engage the filament and carry it to a position adjacent such spindle and so that such filament enters between the said flange and plunger head, means for moving the tailstock to grip a new core between the centres and cause the core to push back the plunger head on to the filament, means for returning the filament-collector to the tailstock end of the machine before commencing winding and means for ejecting the wound package from the package-gripping means, said package-gripping means comprising a pair of resiliently mounted rollers which, with the ejection means, provide a triangulated hold for the package.

14. A winding station for an automatic winding machine for producing a wound package by winding a filament on to a core while held between centres, comprising package-gripping means adjacent to the said centres, means for moving the package-gripping means into gripping engagement with a wound package held between said centres, said centres consisting of a winding spindle and tailstock respectively, means for moving the tailstock axially of, and away from, the core to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound package to a waiting position so that the filament leading thereto is held in tension in a predetermined position for further manipulation and means for ejecting the wound package from the package-gripping means, said means for moving the package-gripping means to release the core from the winding spindle comprising a lever pivotally mounted on the machine at one end connected to tailstock at the other end and connected intermediately of its ends to the package-gripping means so as to move the latter simultaneously with the tailstock but through a smaller distance.

15. A winding station for an automatic winding machine for producing a wound package by winding a filament on to a core while held between centres, comprising package-gripping means adjacent to the said centres, means for moving the package-gripping means into gripping engagement with a wound package held between said centres, said centres consisting of a winding spindle and tailstock respectively, means for moving the tailstock axially of, and away from the core to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound package to a waiting position so that the filament leading thereto is held in tension in a predetermined position for further manipulation and means for ejecting the wound package from the package-gripping means, said means for moving the package-gripping means to release the core from the winding spindle comprising a lever pivotally mounted on the machine at one end connected to tailstock at the other end and connected intermediately of its ends to the package-gripping means so as to move the

latter simultaneously with the tailstock but through a smaller distance and said package-gripping means comprising a pair of resiliently mounted rollers which, with the ejection means provide a triangulated hold for the package.

16. A winding station for an automatic winding machine for producing a wound package by winding a filament on to a core while held between centres, comprising package-gripping means adjacent to the said centres, means for moving the package-gripping means into gripping engagement with a wound package held between said centres, said centres consisting of a winding spindle and tailstock respectively, means for moving the tailstock axially of, and away from, the core to withdraw it from the core, means for moving the package-gripping means towards the tailstock, for a distance less than the movement of the latter, so as to move the package axially in alignment with the centres and withdraw the core from the winding spindle, means for moving the package-gripping means away from the centres to carry the wound package to a waiting position so that the filament leading thereto is held in tension in a predetermined position for further manipulation, filament-receiving and clamping means on the winding spindle, comprising a flange secured to the winding spindle and a plunger head axially movable thereto but constrained to rotate with the spindle, a light spring normally holding the plunger head away from the flange but adapted to be over-powered by axial holding pressure on the core, filament collector means normally adjacent the tailstock, means for moving the filament collector means towards the winding spindle so as to engage the filament and carry it to a position adjacent such spindle, and so that such filament enters between the said flange and plunger head, means for moving the tailstock to grip a new core between the centres and cause the core to push back the plunger head on to the filament, means for returning the filament-collector to the tailstock end of the machine before commencing winding, means for ejecting the wound package from the package-gripping means, said package-gripping means comprising a pair of resiliently mounted rollers which with the ejection means provide a triangulated hold for the package and said means for moving the package-gripping means to release the core from the winding spindle comprising a lever pivotally mounted on the machine

at one end connected to tailstock at the other end and connected intermediately of its ends to the package-gripping means so as to move the latter simultaneously with the tailstock but through a smaller distance.

17. In an automatic winding machine the combination of a pair of gripping members resiliently urged towards each other to grip the sides of a wound package, a base support between adjacent said gripping members cooperating with the gripping members, said gripping members and base support being circumferentially spaced about the package and forming a three point engagement with the wound package, and means for moving the base support relative to the gripping members to eject the package therefrom.

18. In an automatic winding machine as claimed in claim 17, a variable positionable stop provided normally to locate the base support.

19. In an automatic winding machine the combination of a pair of gripping members resiliently urged towards each other to grip the wound package by its sides, an ejector member adjacent said gripping members, said gripping members and ejector member being spaced circumferentially of the package and cooperating to grip the package at three spaced circumferential points and means for moving the ejector member relative to the gripping members to eject the package therefrom.

20. In an automatic winding machine as claimed in claim 17, freely rotatable rollers forming the package-gripping members.

JOHN ROBERT GRADY,
HAROLD L. MUSCHAMP.
